DANIEL J. MAYER, OF BELLEVILLE, NEW JERSEY, ASSIGNOR TO METAL TEXTILE CORPORATION, OF WEST ORANGE, NEW JERSEY, A CORPORATION OF RHODE ISLAND

SCOURING IMPLEMENT

Application filed July 24, 1928. Serial No. 295,105.

This invention relates to an improved construction of scouring device in the form of a hand implement which is especially adapted to provide a mild abradant for scraping, 5 cleaning and polishing the surfaces of utensils and other surfaces desired to be so treated.

The invention has for its principal object to provide a novel construction of device 10 adapted to furnish an abrasive mass made of metallic wire or a composite of metallic wire and vegetable yarn so fabricated as to furnish a multiplicity of closely associated abrasive members or elements rigidly 15 secured at their inner ends to an interior core and radiating therefrom, to thereby produce the desired shape effectively retained against disintegrating, shredding, pulling out, sloughing off, and against other permanent 20 deformation from its desired more or less compact initial shape; the device so made is readily conformable by pressure, however, to the surface to which it may be applied in use, while at the same time it provides 25 a great multiplicity of scraping edges adapted for operative contact with such surface when pressed against and rubbed over the same.

The invention has for a further object to 30 provide an interior binding and carrying core for the abrasive material which may be extended to form or receive the attachment of a suitable handle member.

The invention is clearly illustrated in the 35 accompanying drawings, in which:

Figure 1 is a perspective view illustrating a step in the fabrication of the novel scouring device of this invention;

Figure 2 is a plan view illustrating another step in the fabrication of the scouring device;

Figure 3 is a plan view illustrating still another step in the fabrication of the scouring device.

Figure 4 is a sectional view of the structure shown in Fig. 3.

Figure 5 is a plan view illustrating certain features of the device;

Figure 6 is a plan view of the complete

novel scouring device made according to this invention;

Figure 7 is a side view of the scouring device; and

Figure 8 is a plan view illustrating a variation in the method of assembling the device.

Similar characters of reference are employed in the above described views, to indicate corresponding parts.

In order to more clearly illustrate the essential characteristics of the finished article embodying the construction and principles of the instant invention, there is shown in the drawings, in somewhat diagrammatic fashion, certain steps by which the article 60 may be produced. The article is essentially made of metallic material, preferably in the form of flat ribbon-like wire or wire of angular cross sectional shape which is turned or twisted upon itself to provide a 65 roughly spirally convolved strand or otherwise deformed to provide a multiplicity of lateral, scraping edge projections or points; or the strand or length of material may consist in a flexible carrying core of straight 70 wire or vegetable yarn upon which is carried the spirally convolved or gimped flat metallic wire or wire of angular cross-sectional 75 shape adapted to provide a multiplicity of lateral scraping edge projections or points, 80 as shown, e. g. in Figure 1. Preferably the metallic material employed is of a relatively non-corrosive character; for example copper may be used, both for its relatively non-corrosive character as well as for its comparatively hard nature, whereby its scraping or abrading functions are rendered more efficient.

In making up or assembling any of the forms of metallic material above mentioned 90 to fabricate the same into the novel construction embodying the scouring device according to the principles of this invention, a supporting bar 1 is utilized and a suitable length of the metallic material is wound in 95 a multiplicity of adjacent loops 2 along the length of this bar. Each of the loops 2 has one of its bights 3 extending around and in engagement with substantially one half 100 of the circumference of the bar 1 while its

other bight 4 hangs freely. The bar 1 supporting the loop 2 is then bent upon itself, as illustrated in Fig. 2, to form a U-shaped member having the loops 2 extending along both legs 5 and 6 and along the bottom of the U of this member. This causes the bights 3 of the loops 2 that extend along one of the legs of the U-shaped member to be brought into abutting relation with the similar bights of the loops 2 extending along the other leg of the U-shaped member. The bottom of the U is then held stationary by a suitable clamping device and the free ends of the legs 5 and 6 are gripped and twisted or turned in the direction indicated by the arrows in Figure 3. This twisting of the legs 5 and 6 of the U-shaped member produces a loop 7 at the closed end of this member and causes the legs to be twisted tightly upon one another as illustrated in Figure 3. The bights 3 of the loops 2 are securely gripped between the twisted legs of the U-shaped member and, owing to the large angle of wrap of these bights about the legs 5 and 6, such bights cannot be pulled from between the legs 5 and 6. A portion of the member formed by the twisting of legs 5 and 6 is then bent into substantially circular form as illustrated in Fig. 5 to provide a core 8 having a shank 10. It will be noted from an inspection of Fig. 5 that the loops 2 at one side of the core 8 are entirely independent from and are not continuations of loops on the opposite side of the core. This is important for there is no possibility of a side of a loop pulling through from one side of the core 8 to the other side thereof. Also, since the loops 2 on opposite sides of the core 8 are independent, should the loops on one side wear and become broken off at the core, such wearing will not affect the strength or wearing qualities of the loops on the opposite side of the core 8. This would not be true were the loops on opposite sides of the core but continuations of one another for in that case, since the angle of wrap of such loops upon the legs 5 and 6 would be slight, there would be nothing to prevent the loose woven ends from pulling through in practice and causing the useful loops on the opposite side of the core to drop out, thereby shortening the life of the scouring device considerably. The shank 10 is adapted to be extended itself to provide a handle member, or it may be inserted into and frictionally retained within a recess in a separate handle 11. If desired, the shank 10 may be passed through the loop 7, as illustrated in Fig. 8, thereby tending to strengthen the core 8.

Essentially, in its simplest form, the novel scouring device of this invention comprises metallic material so formed as to provide throughout its length a multiplicity of lateral scraping edge projections 12; said material

being looped upon a supporting member or bar 1 to provide a plurality of loops, each of said loops having one of its bights wrapped substantially 180 degrees around the bar 1 and its other bight free; said bar being bent upon itself and twisted to thereby pinch and rigidly secure the inner wrapped bights of the loops to the bent and twisted bar, whereupon the bar is bent to form a core having a shank for insertion into a handle. The loops radiate outwardly from this core and as these loops are of substantially equal length, the resultant article will preferably possess an ellipsoidal contour, and yet, since the bights 4 are free, a very pliable and conformable mass is provided which retains its shape in use without tendency to shredding, sloughing, and without tendency to become attenuated or lose its generally ellipsoidal conformation. At the same time, the body so formed and constructed readily flattens itself against a surface to which it is applied and over which it is rubbed; a multiplicity of the scraping edge projections 12 acting to efficiently attack the surface so as to quickly remove dirt, encrustations, grease or the like therefrom by the cleansing or scouring abrasion thus afforded.

A very advantageous form of the novel scouring device structure is produced when made of material such as shown in the drawing wherein a carrying strand or core 13 of flexible wire or of vegetable yarn is provided with a gimping of preferably flat metallic wire to form a multiplicity of lateral scraping edge projections 12. The strand or core 13 serves to retain the radiating loops 2 against undue stretching or elongation.

From the above description it will be apparent that a unique and yet very efficient scouring device is provided, which is easy to handle and readily functions to conform itself to a surface upon which it is rubbed; and furthermore the novel retained relation established between the carrying core, and the abrasive strands assures that the article will withstand the rough usage which is inherent in the purposes it is intended to serve, without risk of undue deformation, pulling apart or similar displacement of the abrasive strands of which it is composed.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A device of the kind described comprising, a supporting member, pliable metallic material spirally looped upon said support-

ing member, the loops of said metallic material so formed having their inner bights engaging substantially one-half the perimeter of said supporting member, said supporting member being bent upon itself and tightly twisted to thereby rigidly retain the loops of said metallic material between consecutive convolutions of said twisted supporting member.

10 2. A device of the kind described comprising, a supporting member having a pair of wire strands, and flexible metallic material formed along its length with a multiplicity of lateral scraping projections, said material being continuously looped upon said wire strands, the inner bights of said loops engaging said strands, and said wire strands being twisted together forming overlapping spiral convolutions to thereby pinch the inner bights of said loops between said convolutions to rigidly secure the same to said supporting member against displacement relative thereto.

25 3. A device of the kind described comprising, a supporting member having a pair of wire strands and a connecting portion joining said strands, and metallic flexible material formed along its length with a multiplicity of lateral scraping edge projections, said material being wound along said wire strands and along the connecting portion thereof in a multiplicity of adjacent loops, one bight of each of said loops extending around substantially one half the periphery 35 of one of said wire strands and the opposite end portions of said loops being free, said wire strands being twisted together to effectively retain the said bights of said loops against displacement.

40 4. A device of the kind described comprising, a supporting member having wire strands twisted together with a connecting portion joining said strands, a flexible carrying strand, a gimping of metallic material 45 carried on said strand to provide a multiplicity of lateral scraping projections, said metallic gimped carrying strand being wound along said wire strands and said connecting portion in a multiplicity of adjacent 50 loops, each of said loops having its inner bight extending between adjacent overlying convolutions said wire strands and securely gripped thereby.

55 5. A device of the kind described comprising, a substantially annular core consisting of supporting members twisted together, a flexible carrying strand, metallic wire of angular cross section gimped upon said strand to provide a multiplicity of lateral 60 scraping edges, said gimped strand being looped successively around each of said supporting members so as to engage substantially one-half the perimeter of said members and being securely gripped between 65 said members, said gimped strand forming a

plurality of loops extending radially in all directions from said core.

In testimony that I claim the invention set forth above I have hereunto set my hand this 23rd day of July, 1928.

DANIEL J. MAYER.
